UNITED STATES PATENT OFFICE.

SAMUEL F. DUPREE, JR., GEORGE RITTER, AND AUGUST HECKMAN, OF WILKINSBURG, PENNSYLVANIA.

TOP-OPERATING MECHANISM FOR AUTOMOBILES.

1,143,260.

Specification of Letters Patent. Patented June 15, 1915.

Application filed November 26, 1913. Serial No. 803,169.

To all whom it may concern:

Be it known that we, SAMUEL FRANCIS DUPREE, Jr., GEORGE RITTER, and AUGUST HECKMAN, all of Wilkinsburg, in the county of Allegheny and State of Pennsylvania, have invented a new and useful Improvement in Top-Operating Mechanism for Automobiles, of which the following is a full, clear, and exact description, reference being had to the accompanying drawings, forming part of this specification, in which—

Figure 1 is a side view of an automobile body and top having our invention applied thereto; Fig. 2 is a view partly in side elevation and partly in section showing the operating mechanism at one side of the vehicle on a larger scale; Fig. 3 is a plan view of the same; Figs. 4, 5 and 6 are detail views hereinafter more fully described, Fig. 5 being a section on the line V—V of Fig. 4; Fig. 7 is a rear view of the operating mechanism; Fig. 8 is a wiring diagram showing the electric circuits; Figs. 9 and 10 are detail views of the automatic motor switch; and Fig. 11 is a view similar to Fig. 1, but showing our invention applied to a different construction of vehicle top.

Our invention has relation to mechanism for raising and lowering the tops of automobiles.

The object of the invention is to provide mechanism of simple and effective character whereby an automobile top may be quickly and easily raised or lowered. In the preferred form of our invention, this is accomplished by simply closing the circuit of an electric motor which, through suitable operating gearing, acts to raise and lower the top. Our invention may, however, be carried out by means of manually operated gearing and the term "motive means" as used in the appended claims, is intended to include hand-operated as well as power-operated mechanism.

Our invention will be best understood by reference to the accompanying drawings, which will now be described, it being premised, however, that various changes may be made in the details of construction and arrangement of the several parts, without departing from the spirit and scope of our invention, as defined in the appended claims.

In these drawings, the numeral 2 designates the body of an automobile, and 3 the

top, which may be, in general, of any usual construction.

4 designates the front bow of the top, 5 the rear bow, 6 a rear brace, 6^b another rear brace, 7 a front brace and 8 a horizontal bracing connection between the bows 4 and 5.

In accordance with our invention, the front bows 4 are provided with small roller trucks 8^a at their lower ends, these trucks being mounted for travel in longitudinal guideways or tracks 9, secured to the inner

sides of the vehicle body 2, as most clearly shown in Figs. 4 and 5. These trucks may be of any suitable character. We prefer to provide their wheels 10 with antifriction bearings 11 and also with antifriction thrust

bearings 12. By means of these bearings, the trucks will move freely in the guideways 9 without friction or binding. The upper portions of the bows 4 are pivotally connected at 13 with the lower portions 4^a, which carry these trucks, the latter portions being offset laterally from the edges of the vehicle body shown in Fig. 5. Movement on

the pivotal connection 13 may be restrained in one direction by the lug or finger 13^a (Fig. 4).

The bows are preferably made in two vertically telescoping sections 4 and 4^b with an inclosed tension spring 14, connecting the two telescoping members, as shown in Fig. 1. The purpose of this construction will hereinafter appear.

The lower end of the bow 5 at each side is pivoted on the studs 15, and secured to the lower end of the bow is a segment 16, having its periphery provided with worm gear teeth adapted for engagement with a worm 17 on a side shaft 18. This shaft 18 carries a loose sleeve 19, provided at one end with a bevel gear wheel 20, and at the opposite end with a clutch member 21. The clutch member 21 is adapted to be engaged and disengaged by a coacting clutch member 22, which is keyed to the shaft 18, but is capable of endwise movement thereon. The bevel gear wheel 20 meshes with a bevel gear

23, mounted on a short transverse shaft 24. The shaft 24 at its opposite end carries a bevel gear wheel 25, which meshes with a bevel gear wheel 26 on a vertical shaft 27. The vertical shaft 27 is connected at its lower end through bevel gear wheels 28 and

29 with a jack shaft 30, which extends transversely through the vehicle body. This

shaft is preferably driven by an electric motor 31, which is connected to said shaft through the gears 32. We also preferably provide said shaft with the bevel-gear-driving connections 33, whereby the shaft may (if, for any reason, the motor becomes inoperative) be actuated by means of a detachable hand crank 34. In a cheaper form of the device, the motor and motor connections with the jack shaft may be omitted and the mechanism operated entirely by this hand crank. The vertical shaft 27 carries another bevel gear wheel 35 at its upper end. This wheel meshes with a similar wheel 36, which is loosely sleeved on a shaft 37, parallel with the shaft 18. The wheel 36 of the shaft 37 has clutch teeth 38, which are adapted to be engaged by the teeth of a co-operating clutch member 39, which is secured to the shaft 37 to rotate therewith, but is capable of a reciprocating sliding motion thereon. The shaft 37 has fixed thereto a beveled gear wheel 40, which meshes with a beveled gear wheel 41 on a short transverse shaft 42. The shaft 42 carries a spur wheel or pinion 43, which meshes with a similar wheel or pinion 44, loosely sleeved on one of the studs or stub shafts 15. The sleeve of the wheel 44 carries a bevel gear wheel 45, which meshes with a similar wheel 46, secured to the lower end of a threaded rod 47, which extends upwardly within the bow 5. Mounted on the threaded portion of said rod is a nut 48, having a lug 49, which projects outwardly through a vertically extending slot 50 in said bow and to which is pivotally connected the rear end of the brace 8. When the rod 47 is rotated by the action of the gearing in the manner hereinafter described, the nut 48 is prevented from turning with said rod by reason of the edges of the slot 50. Said nut is therefore caused to travel up or down on the rod according to the direction of rotation of the latter.

The numeral 51 is a three-armed lever which is pivoted at 52. One of the vertical arms of this lever is pivotally connected to the clutch member 22; the other vertical arm 50 is similarly connected to the clutch member 39; and the third rearwardly projecting arm carries a roller 53, which is adapted to engage the surface of the cam 54. This cam is secured to a short transverse shaft 55, having thereon a spur wheel 56, meshing with a pinion 57 on another shaft 58. The shaft 58 has secured thereto a worm wheel 59, which is engaged with and driven by a worm 60, on the vertical shaft 27.

60 61 is a tension spring which is connected to the horizontal arm of the three-armed lever and causes said arm to follow the contour of the cam.

It will be understood that the arrangement of gearing just described is duplicated

at each side of the vehicle, and that the two sets of gearing will be simultaneously operated when the jack shaft 30 is rotated.

The operation is as follows: Supposing the vehicle top to be in its lowered position and it is desired to raise it. The motor-controlling switch 62 (which may be located within convenient reach of the driver's seat, as indicated in dotted lines in Fig. 1), is moved to close the circuit of the motor. At this time, the clutches and the three-armed clutch-operating lever are in the positions shown in Fig. 2. Consequently, the shaft 18 is rotated through the gear connections described, while the shaft 37 remains idle. The rotation of the shaft 18 causes the worm 17 to move the segments 16 in the direction indicated by the arrow in Fig. 2, thereby moving the bows 5 from their backwardly folded position into the position shown in Figs. 1 and 2. During this movement, the worm 60 has been operating the train of gearing connected to the shaft 55, carrying the cam 54. A slight further movement of this cam from the position shown in Fig. 2 causes the roller 53 to fall on to the low portion of the cam. This throws the three-armed lever 51 to a position to reverse the two clutches. That is to say, the clutch member 22 will be thrown out of clutch engagement with the sleeve of the beveled gear wheel 20, and the clutch member 39 will be thrown into engagement with the sleeve of the beveled gear wheel 36. The shaft 18 now ceases to revolve and shaft 37 commences to revolve. This, through the gearing described, rotates the rod or shaft 47 and causes the nut 48 to travel upwardly until the brace 8 is carried to the position indicated in Fig. 1. The movement of the bows 5 and the movement of the braces 8, just described, causes the roller trucks 8^a to move forwardly in their guides, bringing the front bows 4 to the position shown in Fig. 1. This completes the raising of the top. As the bows 4 come to the position shown in Fig. 1, one of them is preferably engaged by the spring catch 63, which holds the bows in their forward raised positions. When it is desired to lower the top, this catch may be released either by hand pressure on the handle 64 of the catch lever, or this may be effected by providing connections, such as indicated at 65 in Fig. 1, with a foot lever or button 66. The forward braces 7 are provided with pins 115 or studs at their lower ends. These pins or studs are adapted to travel in guide slots 68, carried by plates 69, secured to the inner sides of the bows 4, as shown at 67. Each slot 68 is provided with a curved offset 70, at its upper end and with a somewhat similar but reversed offset 71 at its lower end (see Fig. 6). When the parts have been moved to the positions before described, the operator will manually operate the braces 120 125 130

7 to disengage the studs from the lower offset 71 of these slots and push the braces upwardly until said studs come into the upper offset 70. In lieu of this particular adjustment of the braces, we may, however, provide any desired adjustment, such as the detachable cotter pin commonly employed. When the brace 7 is in its lower position, it is substantially parallel with the bows 5, and the top may be readily folded back.

To lower the top, the braces are moved down to their lower position, the spring catch is released, as before described, and the switch 62 is reversed. During the first part of the operation, the clutches remain in their reversed positions, last described, but the shaft 37 is rotated in the opposite direction. This causes the nut 48 to travel downwardly on the rod 47, thus lowering the brace 8 and pulling backwardly the bow 4. As soon as the high part of the cam 54 contacts with the roller 53, the clutches are again thrown to the position shown in Fig. 2, and the shaft 18 is rotated in the reverse direction to that first described. This actuates the segment 16 to move the bow 5 backwardly and downwardly. This draws the front bow backwardly and permits the entire top to assume its lowered folded position. As the front bows 4 move backwardly to their folded positions (and again, when they move forwardly from this position) it will be seen that it is necessary to slightly increase their length, owing to the arcs of movement of the upper ends of the bows 5. The bows 5 may be provided with projections 5^a to engage the bows 4 when the latter are moved back, and thereby elongate the bows 4 against the tension of the said springs. This change in length is provided for by the telescoping connection of the front bows and their spring connections 14, before described. It will be seen that, inasmuch as the center of movement of the bows 5 is coincident with the centers of the gears 44 and 45, the gears 44 will readily roll on the gears 43, as the bows 5 are raised and lowered.

The switch 62 may be of any suitable character. In Fig. 8, we have illustrated diagrammatically the motor circuit. In this diagram, A designates the armature of the motor and F the fields. The switch 62 is provided with one set of contacts *c*, which close the circuit of the motor to rotate it in one direction, and with another set of contacts *c'* which act to reverse the field F to cause the motor to rotate in the opposite direction. The motor is preferably supplied with current from a battery B, which may be the same battery used for the starting mechanism of the automobile.

We preferably provide the motor with an automatic cut-out, whereby it will not overrun in either direction. This cut-out may be of any desired character. One form of

such cut-out is illustrated diagrammatically in Fig. 8. Its general arrangement is shown in rear elevation in Fig. 7 and further details thereof are shown in Figs. 9 and 10. As shown in these figures, the cut-out switch 70 comprises three parallel conductor bars 72, 73 and 74, to which are connected three different leads from the motor circuit. The bar 72 is provided at one end with an insulating portion 75, and the bar 73 is provided at its opposite end with a similar insulating portion 76. 77 is a transverse bridging conductor which is sleeved to slide back and forth on the conductors 72, 73 and 74. This member has a nut portion 78, which engages 80 the thread of a threaded shaft 79, connected at one end by gears 80, with the jack shaft 30, as best shown in Fig. 7. When the bridging member 77 is in the position shown in Fig. 9, it forms a circuit connection between 85 the conductors 73 and 74, but is in contact with the insulating portion 75 of the conductor 72. When moved to its other extreme position, it bridges the conductors 72 and 74, but engages the insulating portion 76 of 90 the conductor 73. As the details of this switch and the motor circuits form no part of our invention, it will be unnecessary to follow out the circuit paths in detail, and the positions of the switch 62 and of this 95 cut-out switch. These circuits may be readily traced on Fig. 8, if desired. It will be readily seen, however, that in each extreme position of the member 77, the motor circuit will be open, thereby stopping the motor. 100 The thread of the shaft 79 and the gears 80 are so proportioned that this opening of the circuit will occur in one direction when the bows are in the position shown in Fig. 1, and will occur in the other direction when 105 these bows have been moved to their backwardly folded positions. We preferably provide the supporting stops 81 for said bows when in their forward positions, thereby relieving the gearing from strains. 110

The gearing at each side of the vehicle may be protected by suitable casings, such as indicated at 82 in Fig. 7. The major portion of this gearing, together with the jack shaft, the motor and the automatic cut-out 115 switch, may be conveniently located within the body of the vehicle underneath and at the side portions of the rear seat, as shown in Figs. 1 and 7. By locating this mechanism in this manner, it is almost entirely 120 out of sight and it is also protected from the weather, dust, dirt, etc.

Inasmuch as the guideways or tracks 9 for the roller trucks of the front rollers necessarily have portions thereof carried by 125 the rear side doors 83, and as it is necessary that these doors shall be closed when the top is being raised or lowered, we preferably provide means whereby the circuit of the motor will only be closed when both side 130

doors are closed. This may be readily effected by carrying the motor circuit in series through contacts 84 controlled by the rear doors. That is to say, the contacts 84 are closed, and therefore, the motor circuit is closed only when the doors are closed.

In Fig. 11, we have illustrated the application of our invention to an automobile of the roadster type having a differently constructed and lighter top. In this form of top, there are no front bows which require to be moved forward and back in raising and lowering the top. All that is necessary is to move the bows 85 on their pivotal centers and to raise and lower the side braces 86. The operating mechanism for this form of top is in all respects similar to that before described. The bows 85 are moved by the same gears, and so also the nuts 87 which travel in said bows and which are similar to the traveling nuts before described. The only difference is that the braces 86 connected to these nuts extend directly to the forward part of the vehicle top instead of to movable front bows. In this form, therefore, the tracks or guideways for the front bows are unnecessary and are omitted. We have, however, in this figure shown the hand crank 88, for raising and lowering the top, as extending forwardly underneath the seat from the shaft 34, instead of rearwardly therefrom as in Fig. 1.

The advantages of our invention will be readily appreciated by those familiar with the raising and lowering of automobile tops. This operation has usually been carried out by hand and is a somewhat difficult one, especially for one person. The tops are heavy and care must be exercised in raising and lowering them to see that the portions of the braces which are usually detached at their lower ends do not contact with and abrade or otherwise mar the vehicle body. Our invention provides mechanism which can be operated either by an electric motor or by hand or mechanical power, and by which the raising and lowering can be substantially all effected without manual movement of the bows and braces. The only hand manipulation of these parts which is required is the moving of the braces 7 from one position to the other. In other respects, the entire top is moved from its lowered to its raised position and vice versa through the action of the described mechanism.

Our invention can be applied to a car at a relatively low cost; does not in any way detract from the appearance of the car, being practically all concealed; and the raising and lowering of the top at any time desired is a simple and easy matter.

While we have described our preferred mechanism in detail, it will be obvious that the details may be changed in various ways. Thus, we may employ any suitable arrange-

ment of gearing, the details of bow construction and arrangement may be changed, and any suitable form of electric switches may be provided for controlling the operation of the motor, when the motor is employed.

We claim:

1. A folding vehicle top having pivoted rear frame members and forwardly and backwardly sliding foldable front frame members, adjustable braces between the two members, gearing connected to the rear members to move the same on their pivots, other gearing connected to the bracing members, and motive means for actuating said 70 gearings, substantially as described.

2. The combination with a vehicle body having side guides or tracks, of a foldable top having frame members mounted to run in said guides or tracks, gearing for moving 85 said members, and a motor for actuating said gearing, portions of said tracks being carried by the vehicle doors and said doors having contacts which in part control the circuit of said motor, substantially as de- 90 scribed.

3. A foldable vehicle top having hollow, slotted, pivoted, rear bows, and front frame members, gearing connected to said bows to move the same on their pivots, threaded rods 95 extending through said bows and nuts arranged to travel on said rods, gearing for rotating the rods, and bracing members extending from the nuts to the front frame members of said top, substantially as de- 100 scribed.

4. A foldable vehicle top having a foldable frame member, gearing for moving said frame member on its pivot to raise and lower the same, said top also having a brace 105 member connected thereto, and other gearing for moving the brace member into and out of bracing position, substantially as described.

5. A foldable vehicle top having a hollow, 110 slotted bow, gearing connected to said bow to move it on its pivot, a threaded rod extending through the bow, a nut arranged to travel on said rod, gearing for rotating the rod, and a top-bracing member connected to 115 the nut and to the top together with means for operating said gearing, substantially as described.

6. The combination with a folding vehicle top having pivoted rear bows, slideable 120 front bows, and connections between the rear and front bows, of gearing for moving the rear bows on their pivots, other gearing for effecting a sliding movement of the front bows, motive means for actuating both 125 gearings, clutch mechanism co-operating with said gearings for throwing one gearing out of operation and the other gearing into operation, and clutch-shifting mechanism controlled by the movements of said 130

gearings, together with other means actuated by the motor for controlling its own supply circuit; substantially as described.

7. The combination with a folding vehicle top having pivoted rear bows, slideable front bows and connections between rear and front bows, of gearing for moving the rear bows on their pivots, other gearing for effecting a sliding movement of the front bows, motive means for actuating both gearings, clutch mechanism coöperating with said gearings for throwing one gearing out of operation and the other gearing into operation, and clutch-shifting mechanism controlled by the movements of said gearings; substantially as described.

8. The combination with a folding vehicle top having pivoted rear bows, and slideable front bows, a gearing connected to one of the rear bows at each side of the vehicle for turning said bows on their pivots, other gearing connected to the front bows at each side for moving the top to effect a sliding movement of the front bows, a motive device arranged to drive both gearings, and automatic clutch mechanism for alternately connecting the said device with one and the other of said gearings; substantially as described.

30 9. A folding vehicle top having pivoted rear frame members, and forwardly and backwardly sliding front frame members, braces connecting the front and rear members, gearing connected to the rear members, other gearing connected to the braces,

a motive means for actuating both gearings, and automatic clutch mechanism for throwing the two gearings alternately into and out of operation; substantially as described.

10. A vehicle having a foldable top, said top having pivoted rear frame members and forwardly and backwardly slideable front frame members, braces connecting the front and rear members, and actuating shaft extending transversely of the rear portion of the vehicle independently of the axles, gearing for connecting each end portion of said shaft with the adjacent rear bows, other gearing for connecting each end portion of said shaft with the brace members, and clutch mechanism for controlling the two gearings; substantially as described.

11. A vehicle having a foldable top, said top having pivoted rear bows and slideable front bows, grooved guide ways on the sides of the vehicle body with which said front bows have a slideable engagement, motive means connected to the rear bows to move them on their pivots, and actuating connections to the front bows to slide them in said guides; substantially as described.

In testimony whereof, we have hereunto set our hands.
